Primary Examiner — Carol P Rademaker(74) *Attorney, Agent, or Firm* — Knechtel, Demeur & Samlan(57) **CLAIM**

I claim the ornamental design for a bottle, as shown and described.

DESCRIPTION

FIG. 1 is a top, front, left side perspective view of the bottle; FIG. 2 is a bottom, rear, left side perspective view thereof; FIG. 3 is a front elevational view thereof, the rear elevational view being the same; FIG. 4 is a left side elevational view thereof, the right side elevational view being the same; FIG. 5 is a bottom plan view thereof; and, FIG. 6 is a top plan view thereof. The broken line shown in FIGS. 1 & 6 of the inside edge of the pour spout is included for the purpose of illustrating environmental structure and forms no part of the claimed design.
